UNITED STATES PATENT OFFICE.

DAVID BAKER, OF FREEPORT, PENNSYLVANIA.

CAR-COUPLING.

SPECIFICATION forming part of Letters Patent No. 376,700, dated January 17, 1888.

Application filed April 18, 1887. Serial No. 235,280. (No model.)

To all whom it may concern:

Be it known that I, DAVID BAKER, a citizen of the United States, residing at Freeport, in the county of Armstrong and State of Pennsylvania, have invented certain new and useful Improvements in Car-Couplers; and I do declare the following to be a full, clear, and exact description of the invention, such as will enable others skilled in the art to which it applies to make and use the same, reference being had to the accompanying drawings, and to the letters and figures of reference marked thereon, which form a part of this specification.

15 The special object of the invention is to improve the action of car-couplers by providing a link-raiser which shall render the coupling certain when two cars are brought together.

Figure 1 of the drawings is a plan view; 20 Fig. 2, a side elevation, and Fig. 3 a vertical longitudinal section.

In the drawings, A represents the car, and B the draw-head, having top and bottom pin-holes, b b'. Over the latter and on top of the 25 draw-head is the guide-tube B', which carries on the inside near its top a pulley, C. The pin D has a chain attached at one end to its head, passing over the pulley C and secured to the upper end of a lever, E, which is bottom-pivoted at e to the draw-head and has the opening e' between its arms E' E'. Through the opening e' passes the front end of the arm f on the shaft F, which has the hand-cranks f' f' at the sides. When the shaft F is turned, 30 as shown in Fig. 2 of the drawings, the arm f draws the lever E back and pulls on the chain d until the pin D is lifted from the link and allows said link to be withdrawn from the draw-head. On the other hand, when it is 35 desired to drop the pin into the link in order to couple two cars, the shaft is turned in an opposite direction downward, as shown in Fig. 40 3 of the drawings, when the weight of the pin will pull the lever forward and drop by its 45 own gravity into the link.

G is my link-raiser, having the bends g g' g² g³ and the incline g⁴, as well as the lifting end

g⁵. It is pivoted at g⁶ to the rods H, which are guided at the rear in the keepers h. K is a guide-bar having the guide-slots k k for the 50 rods H and the guide-slots k' k' for the link-raiser G. It has also an opening, k², in which is received the draw-head, to which it is securely fastened.

When a car is to be coupled with another, 55 the link-raiser is drawn forward, as shown in Fig. 2 of the drawings, and as the two cars approach each other the rods H strike the car carrying the link and are pushed back in their guides, so as to carry back the link-raiser G. The latter, as its incline g⁴ is moved back over the bottom of the guide-slots k' k', is raised until the end g⁵ lifts up and holds the link until its end rests on the inside of the draw-head, when, the bend g being over the 60 guide, the link-raiser G drops and is supported between the bends g' g², as shown in Fig. 3 of the drawings.

Having thus described all that is necessary to a full understanding of the invention, what 70 I claim as new, and desire to protect by Letters Patent, is—

1. The combination, with a draw-head having the pin-holes b b', of the superposed tube B', carrying the inside pulley C, the pin D, 75 carrying a chain, the lever E, and the shaft F, having the arm f, as and for the purpose described.

2. The link-raiser G, having the incline g⁵, 80 in combination with guide-bar K, having grooves k' k', whereby the former may rise as it is carried back to lift the link, in the manner set forth.

3. The movable rods H, combined with a thereto-pivoted link-raiser, G, both moving 85 in guides and operating together, as and for the purpose specified.

In testimony whereof I affix my signature in presence of two witnesses.

DAVID BAKER.
